UNITED STATES PATENT OFFICE.

JAMES J. PARRIS, OF BEAVER FALLS, PENNSYLVANIA.

CARBURETING APPARATUS.

SPECIFICATION forming part of Letters Patent No. 484,721, dated October 18, 1892.

Application filed July 23, 1891. Serial No. 400,511. (No model.)

To all whom it may concern:

Be it known that I, JAMES J. PARRIS, a citizen of the United States, residing at Beaver Falls, in the county of Beaver and State of Pennsylvania, have invented certain new and useful Improvements in Carbureting Apparatus, of which the following is a specification.

This invention relates to apparatus for carbureting air or gas, as fully set forth herein-after, and as illustrated in the accompanying drawings, in which—

Figure 1 is a longitudinal sectional elevation, and Fig. 2 a plan view.

In the apparatus there is a number of chambers, as shown, three chambers contained in three tanks or casings F F' F'', in the first of which there is placed a body of crude oil, the surface line being shown in dotted lines, and a gage G, serving to enable the attendant to determine the amount. In the second chamber there is a more volatile liquid or mixture—say one-half crude oil and one-half gasoline, No. 70 test—and in the third a more volatile liquid is employed, as gasoline. I pass a current of air or other gas to be carbureted successively through the contents of the three chambers, and by using liquids of different characters, as described, I bring the uncarbureted air or gas first into contact with the less volatile liquid, and then as the air becomes more fully charged I pass it through the more volatile liquid, and by this means secure a more perfect saturation than would otherwise be possible.

In order to bring the air or gas more intimately into contact with the liquid than would result from permitting it to flow directly upward, I provide each casing with a series of deflectors and introduce the air at the bottom, so that it makes a circuitous or zigzag upward course, and is divided into small bubbles. Thus each casing has a series of horizontal diaphragms m n, and the inlet-pipe a extends downward through the lowest diaphragm or partition n, and the space between the latter and the bottom of the casing is divided by perforated partitions b b, and each partition n is solid at the center and perforated near the outer edge, while the partitions m are perforated near the center and solid near the outer edges. As a result the air is di-

vided in passing through the perforations b and further divided as it passes through the successive partitions m n, and is also compelled to travel back and forth horizontally until it reaches the space above the surface of the liquid. From each vessel the air passes through a pipe a' to the pipe a of the next vessel, the pipes a a' being connected by a suitable coupling B, that permits them to be readily disconnected when detached. The air is forced into the pipe a of the first vessel F by means of a pump or other suitable blowing apparatus—as, for instance, a Blackman fan D—and a check-valve c, in a casing D, prevents a backflow toward the fan, while a check-valve c' in a casing d' in the line of the pipe a', extending from the last casing F'', prevents any backflow of the saturated air through the apparatus.

When the liquid becomes too thick or it is otherwise desirable to empty one of the casings, it may be drawn off through a cock e, and a filling apparatus E may be used with each casing to permit the liquid to be introduced regardless of the pressure therein. This apparatus consists of a casing f, communicating with a funnel g through a pipe provided with a cock h, and the casing or vessel f communicates with the casing F below through a pipe j, provided with a cock s, that extends below the level of the liquid in the lower casing, and through a pipe I, that projects nearly to the top of the vessel f and communicates with a space above the liquid of the lower casing. The liquid is poured into the funnel while the cock h is closed. The cocks s t are then closed and the cock h opened to allow the liquid to pass to the vessel f. The cock h is then closed and the cocks s t opened, when the liquid will flow downward into the chamber below.

It will be evident that in carrying out my invention the chambers may be in casings of different forms and the deflectors may be differently constructed.

Without limiting myself to the precise construction and arrangement of parts shown and described, I claim—

In a carbureting apparatus, the combination of the tank or casing, a series of diaphragms m and n, extending across the tank, the diaphragms m being perforated near their

centers and the diaphragms n near their outer edges, an inlet-pipe leading into the tank and opening near the bottom thereof below the lowest diaphragm n , means for forcing a current of gas under pressure through the inlet-pipe, and the inclined perforated partitions b , placed between the lowest diaphragm and the bottom of the casing and extending between the open end of the inlet-pipe and the perforated edge of the diaphragm n , whereby the

gas is broken up or divided before reaching the perforations in the first diaphragm, substantially as described.

In testimony whereof I have signed my name to this specification in the presence of 15 two subscribing witnesses.

JAMES J. PARRIS.
